TEXTILE FABRIC

Elizabeth Klein, Yonkers, N. Y., assignor to Chicopee Mills, Inc., a corporation of New York

Application April 27, 1955, Serial No. 35,706

Term of patent 14 years

(Cl. D92—1)

The figure is a plan view of a textile fabric showing my new design.

My design comprises a coarse honeycomb mesh of tinsel strands interwoven with and overlying a net background of contrasting color, as shown.

I claim:

The ornamental design for a textile fabric, as shown and described.
